CODED TRACK CIRCUIT SIGNALING
SYSTEMSedgwick N. Wight, Rochester, N. Y., assignor to
General Railway Signal Company, Rochester,
N. Y.

Application July 26, 1941, Serial No. 404,212

19 Claims. (CL 246—38)

This invention relates to single track railway signaling systems and more particularly to a coded track circuit of the duplex type for such system.

By a duplex coded track circuit is meant a track circuit in which there is a track relay at each end thereof which responds to a code applied to the other end thereof and wherein codes may be applied at either or both ends simultaneously and received at the opposite end from that at which they are applied.

In accordance with the present invention it is proposed to apply pulsating alternating current across the rails at opposite ends of the same track circuit in such a manner that a wave of one polarity is applied during the first half of a cycle of alternating current at one end of the track circuit and so that a pulsating current of the opposite polarity waves is applied during the second half of each cycle of an alternating current. In other words, pulses of direct current are alternately applied to opposite ends of the track circuit at a rate corresponding to the frequency of the alternating current employed, and in such a manner that one of the rails of the railway track alternately become plus (+) and minus (—) once for each cycle of alternating current. That is, current of the same polarity is alternately applied to one and then the other of the track rails. In this proposed construction these pulses of direct current are derived from a rectifier of the static type as distinguished from a rectifier of either the vibrating reed or the commutating type. In the prior application of Hoppe Ser. No. 253,837 pulsating currents are similarly applied to opposite ends of a track circuit by a vibrating reed actuated from the same source of alternating current. If a vibrating reed is used for obtaining pulsating direct current from an alternating current system such, for instance, as is disclosed in the Hoppe application above referred to, there is little danger of obtaining a false clear indication, this by reason of the fact that a vibrating reed rectifier does not readily become short circuited. If, however, a rectifier of the static electro-lytic or copper-oxide type is employed, as is proposed in the system of the present invention, a false clear indication could very easily be given by such rectifier becoming short circuited, as is very commonly the case with static rectifiers of this type, were it not for the provision of suitable checking means.

In accordance with the present invention it is proposed to employ a rectifier of the static cop-

per-oxide type for applying such pulsating current to the track circuit and also for detecting the polarity of the pulsating current received at the track relay end of such track circuit, it being further proposed to employ a track relay of the polar type connected in series with a rectifier of the single wave type to detect pulsating current of a particular polarity. It is also proposed to employ suitable checking means for causing an associated signal to indicate stop when either one of these static rectifiers breaks down.

Other objects, purposes and characteristic features of the present invention will in part be pointed out in the specification hereinafter and will in part be obvious from the accompanying drawing which:

Fig. 1 shows the invention applied to one section of railway track at the entrance to each end of which there is located a signal for governing the entrance of traffic into such section; and

Fig. 2 shows a modified form of the invention.

Structure

Referring to Fig. 1 of the drawing, the track rails 10 of a railway track have been shown divided into blocks or sections by insulating joints 12 of which the block N and the adjacent ends of the blocks M and O only have been illustrated. At the left end of the block N is shown a signal S2 which governs the movement of east-bound traffic into the block N and at the east end of this block N is shown a signal S1 which governs west-bound traffic into this block. These signals S2 and S1 are controlled respectively by circuits and apparatus which have been conventionally shown by dotted rectangles which have been designated EC and WC, respectively, and which circuits and apparatus are controlled by the associated track and check relays presently to be described. This apparatus EC or WC includes the usual de-coding apparatus and directional stick relay control circuits and apparatus well known in the art, such, for instance, as are illustrated in the prior application of Hoppe above referred to. The code following track relay for governing east-bound traffic has been designated CFTE and is connected in series with a rectifier R3E and across the track rails 10 at the west end of the block N, in which reference characters the letter "E" denotes apparatus for governing east-bound traffic. This code following track relay CFTE receives its energy from the secondary winding of a transformer TE having a rectifier R1E included in series therewith and lo-

cated at the east end of the block N. The secondary winding of the transformer TW is also provided with the usual series impedance IE. Identical apparatus is employed for governing west-bound traffic of which each element has been designated by the same reference character except that the letter "W" has been substituted for the letter "E." Also the pulsating current supplied by the transformer-rectifier TW-RW has been illustrated by solid arrows, whereas the pulsating current supplied by the transformer-rectifier TE-RE has been illustrated by dotted arrows.

It is readily seen that failure of the rectifier R3E, for instance, by becoming short circuited, would allow the code following track relay CFTE to become energized by current of either polarity. For this reason, the check relay CK1E has been connected in multiple with the rectifier R3E. This provision is resorted to in order to further assure against false operation of the track relay CFTE. This track relay has also been made polar, it being provided with a polar contact 15E which may be operated from its biased position, to which it is biased by a spring 16E, only if the current applied thereto is of the proper polarity, such as is permitted to flow through the rectifier R3E. It is readily seen that if the rectifier R1W connected in series with the secondary winding of the transformer TW should break down or become short circuited it could directly apply current, at least intermittently, to the code following track relay CFTE through the medium of the rectifier R3E, because such break down of rectifier R1W would allow both waves of each cycle of alternating current to flow. For this reason, a second check relay CK2W has been connected to receive energy from the secondary windings of the transformer TW, which energy is pulsating current derived by rectification of this alternating current by the rectifier R1W. This check relay CK2W is of such construction that it will pick up its armature and close its front contacts if pulsating current is applied thereto but which will drop to its deenergized retracted position if thereafter alternating current is applied thereto, assuming of course that these currents are derived from the same source of alternating current potential, the pulsating current thereof being rectified by the rectifier R1W. It is, therefore, readily seen that the breaking down or short circuiting of the rectifier R1W will be manifested by the dropping of the check relay CK2W. This circuit, including the secondary winding of the transformer TW, the rectifier R1W, and the check relay CK2W and the series impedance IW heretofore mentioned in connection with apparatus located at the east end of the block N and there designated IE, checks the rectifying effectiveness of the rectifier R1W. Attention is directed to the fact that the coding contact 15E can only apply coded currents to the decoding and directional control apparatus EC if both of the relays CK1E and CK2W are energized, as is evident from the front contacts 17E and 18W, respectively, of these relays included in series with the contact 15E of the code following track relay CFTE. Since the apparatus at both ends of the block N are identical like devices used for west-bound traffic have been designated by the same reference characters as those for east-bound traffic except that suffixes W have been used instead of suffixes E.

At this point it may be well to give some addi-

tional explanation as to the operating characteristics of the relays involved. The track relays CFTE and CFTW are polar devices so that they will not respond to the polarity of currents passed by the rectifiers R1W and R1E, respectively, local thereto but will respond to the polarity of current passed by the rectifiers R1E and R1W, respectively located at the ends of the block opposite to such relays. These track relays CFTE and CFTW are very quick acting so that they are capable of following the impulses of the fastest code assumed to be 120 impulses per minute in the particular system specifically disclosed and at the same time these track relays are not fast enough to follow the pulses of the pulsating current which may be of from 60 to 100 pulses per second. For this reason these track relays have been called code following track relays. The check relays CK1E and CK1W, on the other hand, are not code following in their speed of operation but instead are slow enough dropping to stay up between impulses of the slowest code assumed to be a code of 75 impulses per minute in the system disclosed. It is thus seen that the check relays CK1E and CK1W will during non-occupied conditions of the block N remain energized continuously assuming, of course, that the rectifiers R3E and R3W are in good rectifying condition but that these check relays will assume their deenergized position during occupancy of the block N at some point not too great a distance from the end at which such check relay is located. In other words, the check relays CK1E and CK1W may be used to indicate occupancy for approach indication purposes or for picking up a directional stick relay. For instance, a back contact of relay CK1E may be used to pick up the directional stick relay for signal S2 in the same way as back contacts 30 and 31 in said Hoppe application are used to pick up a directional stick relay.

It is readily understood that the breaking down, or becoming short circuited, of the rectifiers R2E or R3E will cause dropping of the relays CFTE or CK1E, respectively. The drop away characteristics of these relays CFTE and CK1E is such that the open circuiting of the rectifiers R2E or R3E will cause dropping of the relay in series therewith, namely, the relay CK1E or CFTE, respectively. Furthermore, the check relay CK1E will drop upon open circuiting of the rectifier R1W, whereas for reasons already explained the check relay CK2W will drop upon the rectifier R1W becoming short circuited. The rectifier R2E has three important functions to perform. One, it serves to allow current for the check relay CK1E to flow; two, it prevents the current flowing through relay CK1E from flowing through track relay CFTE; and three, it renders track relay CFTE slow dropping to an extent to follow the 75 or 120 impulse per minute code. What has been said about the operating characteristics of the devices at the west end of block N is also true of corresponding devices at the east end of this block.

Since the check relay CK2W as used in Fig. 1 is continuously energized this relay may be used as a repeater relay. Such a construction is illustrated in Fig. 2 where the front contact 25 of the check relay CK1E and front polar contact 26 of the code following track relay CFTE are included in series with the check relay CK2W. In this construction the contact 27 of check relay CK2W alone controls the circuit leading to the decoding apparatus. This construction reduces the

number of contacts required on the code following relay. In all other respects the system of Fig. 2 is constructed and functions the same as that of Fig. 1.

Operation

Let us first assume that each of the blocks N, M and O is unoccupied. Under this condition of traffic, the block N being unoccupied, the coding relay CRW is intermittently energized to cause the coding contact 20W to close and open at a coding rate to create 120 impulses of pulsating current per minute. This pulsating current flows from the secondary winding of the transformer TW, through the rectifier R1W, to the lower track rail 10 then through this rail of the track, to the east end of the block N, through the windings of the code following track relay CFTW, through the rectifier R3W, to the other rail of the block N, back to the west end of the block N, and through coding contact 20W and series impedance IW, back to the secondary winding of the transformer TW. The flow of this current of 120 impulses per minute, of which each impulse constitutes a plurality of direct current pulses, causes the code following track relay CFTW to assume its energized position intermittently 120 times per minute. The pulsating current in the circuit just traced is of such a polarity as to intermittently move the contact 15W to the right against the tension of the spring 16W to actuate the decoding apparatus constituting part of the apparatus conventionally illustrated by the rectangle WC. The potential existing across the secondary winding of the transformer TW also energizes the check relay CK2W by pulsating current of the same polarity as the pulsating current supplied to the code following track relay CFTW, both of these currents being supplied through the medium of the rectifier R1W. As already pointed out, the check relay CK2W is so constructed that it will pick up on pulsating current, but will not be maintained up on alternating current derived from the same transformer from which such pulsating current is derived by rectification. There is still another circuit which is supplied from the secondary winding of the transformer TW, namely, the circuit including the rectifier R1W, the check relay CK1E, the rectifier R2E, the coding contact 20W, and the series impedance IW. The current in the circuit just traced flows through the check relay CK1E and maintains this check relay energized so long as the rectifier R3E is not broken down and the block N is not occupied. If the rectifier R3E should break down it would create a shunt around the relay CK1E causing this relay to assume its deenergized position. It is again pointed out that this check relay CK1E is so slow dropping that it will not drop between the pulses of either the 75 impulse code or the 120 impulse code applied through the coding contact 20W. If neither a code of 75 impulses per minute or a code of 120 impulses per minute is applied to the coding relay CRW, the coding contact 20W assumes its deenergized position continuously and causes pulsating direct current to be applied to the track circuit and to the check relay CK1E continuously. It is thus seen that the transformer TW supplies pulsating current continuously to the checking relay CK2W and supplies pulsating current intermittently to the check relay CK1E and the code following track relay CFTW at the opposite end of the block and in accordance with the code then applied to the coding relay CRW. In the same manner as the transformer TW applies pulsating current at

either the 75 or 120 impulse per minute coding rate to the west end of the block N the secondary winding of the transformer TE applies similar pulsating current coded at either the 75 or the 120 impulse per minute code rate to the east end of the block N, and this coded current may flow through the check relay CK1W and through the code following track relay CFTE. Similarly, a pulsating current is applied to the check relays CK1W and CK2E from the secondary winding of the transformer TE.

Under normal clear traffic conditions, as has just been assumed, both of the coding relays CRW and CRE are energized and deenergized at the 120 impulse per minute coding rate, as a result of which both of the code following track relays CFTE and CFTW are energized intermittently 120 times per minute, which results in the code following contacts 15E and 15W assuming their right-hand position 120 times per minute. Also, for reasons just explained the check relays CK1E and CK2W, as well as the check relay CK1W, and the check relay CK2E, assume their energized position continuously, whereas the code following track relays CFTE and CFTW are intermittently picked up at the 120 times per minute rate. The contacts 17E, 18E, 17W and 18W are, therefore, continuously closed and the contacts 15E and 15W are intermittently operated to the right-hand actuated positions. This actuation of these contacts 15E and 15W at the 120 times per minute rate causes the decoding devices constituting part of the apparatuses EC and WC, respectively, to close clearing circuits for the signals S2 and S1, respectively.

Let us now assume that an east-bound train approaches in the block M. This causes the coding relay CRW to be energized intermittently at the 75 impulse per minute code rate by suitable apparatus not shown. This results in intermittent energization of the code following track relay CFTW at the 75 times per minute rate and in turn causes the decoding devices in apparatus WC to close a circuit to actuate the signal S1 to its caution indication condition. This circuit constitutes part of the signal control circuits conventionally illustrated by the dotted line 19W.

Let us now assume that the east-bound train in the block M passes the signal S2 and moves into the block N. This results in continuous deenergization of both of the code following track relays CFTE and CFTW and results in both of the signals S2 and S1 being controlled to display a stop indication, because during such occupancy of the block N no coding current from the transformers TE and TW can reach the track relays CFTE and CFTW, respectively, and the code following contacts 15E and 15W will remain at rest and cause the de-coding apparatus EC and WC to manifest danger traffic conditions.

Let us now assume that the train under consideration has passed entirely through the block N and through the block O and that all of the apparatus returns to its normal condition in which both of the signals S2 and S1 display a clear indication. Let us also assume that the rectifier R3E has become short circuited. This will result in the pulsating current formerly flowing from the secondary winding of the transformer TW, the rectifier R1W, the check relay CK1E, the rectifier R2E, and the coding contact 20W to flow through the broken down rectifier R3E instead of through the check relay CK1E. In other words, the check relay CK1E will as-

sume its deenergized retracted position and open the circuit leading to the decoding apparatus contained within the rectangle EC and cause the operation of the signal S2 to its danger or stop condition. Similarly, if the rectifier R1W should become short circuited, this would result in alternating current instead of pulsating current being applied to the check relay CK2W, as a result of which this check relay CK2W would assume its deenergized retracted position. If the track relay CFTE were not constructed polar and this latter check were not provided the coding contact 20W could, through the medium of the secondary winding of the transformer TW, the rectifier R1W, the broken down rectifier R3E, supply pulsating current to the code following track relay CFTE and hold the signal S2 falsely clear by a locally generated code. This pulsating current is, however, of the wrong polarity and since the code following track relay CFTE is a polar relay, no false clear indication would be given under the assumed conditions at a particular end of the block N due to the coding apparatus located at the same end. The relay CK2W picks up on pulsating current and drops away on alternating current because the inductive reactance is much greater for alternating current than for pulsating current of unidirectional polarity. Although the code following relay CFTE has not been employed to check the rectifier R2E, nevertheless it does produce such checking effect, because if the rectifier R2E should become short circuited the code following relay CFTE would assume its deenergized biased position continuously. What has been said about the apparatus at the west end of the block N is likewise true of the apparatus at the east end of the block N.

Stating this functioning of the apparatus in somewhat different terms the rectifier R1W prevents the application of pulsating current of the wrong polarity to the rails at the west end of the block N so that this pulsating current of the wrong polarity cannot operate the code following track relay CFTE at the west end of the block. The check relay CK1E has been provided to check the rectifying effectiveness of the rectifier R3E which is included in series with the code following track relay CFTE. This check relay CK1E is, therefore, provided to open the circuit controlled by the contact 15E of the code following track relay CFTE in the event that this code following track relay CFTE is energized by local current which flows through the rectifier R3E. The rectifier R2E has primarily been employed to provide a path for the current which flows through the check relay CK1E and secondarily makes the track relay CFTE sufficiently slow dropping so as not to chatter in response to the pulses of the pulsating current and yet is fast enough acting to follow the high code of 120 impulses per minute.

Having thus shown and described one specific embodiment of applicant's invention it is desired to be understood that the particular embodiment illustrated has been selected to facilitate description of the apparatus embodying the invention and the disclosure of the functions it performs, and it is further desired to be understood that various changes, modifications and additions may be made to the invention without departing from the spirit or scope thereof, except as demanded by the scope of the following claims.

What I claim as new is:

1. In combination with a section of track divided from adjacent sections by insulating joints,

a single wave rectifier for each end of said section, a track relay for each end of said section each connected in series with the associated single wave rectifier and connected across the rails of said section at that end, said rectifiers being so poled that one rectifier allows current to flow from one rail and the other rectifier allows current to flow from the other rail, a source of alternating current available at both ends of said section, another single wave rectifier at each end of said section, a coding contact at each end of said section, a transformer at each end of said section having its primary winding energized from said source and the secondary windings of which are connected in series with the associated coding contact and said another rectifier, said transformers being so connected and said other rectifiers being so poled in the secondary windings that current impulses are alternately applied to opposite ends of said section each current impulse being of a polarity so that it cannot flow through the track relay and its associated rectifier at that end but can flow through the track relay and its associated rectifier at the other end, a check relay connected in multiple with each rectifier associated with a track relay, and decoding electro-responsive means controlled by the track relay and check relay at one end of said section.

2. In combination with a section of track divided from adjacent sections by insulating joints, a single wave rectifier for each end of said section, a track relay for each end of said section and connected in series with the associated single wave rectifier and connected across the track rails at that end of said section, said rectifiers being so poled that one rectifier allows current to flow from one rail and the other rectifier allows current to flow from the other rail, a source of alternating current available at both ends of said section, another single wave rectifier at each end of said section, a coding contact at each end of said section, a transformer at each end of said section having its primary winding energized from said source the secondary windings of which are so connected in series with the associated coding contact and said another rectifier so that current impulses are alternately applied to opposite ends of said section each current impulse being poled so that it cannot flow through the track relay and its associated rectifier at that end but can flow through the track relay and its associated rectifier at the other end, checking means for checking the rectifying effectiveness of one of said rectifiers, and decoding means at each end of said section controlled by the associated track relay and checking means.

3. In combination with a section of track divided from adjacent sections by insulating joints, a single wave rectifier for each end of said section, a track relay for each end of said section and connected in series with the associated single wave rectifier and connected across the track rails at that end of said section, said rectifiers being so poled in the circuit that one rectifier allows current to flow from one rail and the other rectifier allows current to flow from the other rail, a source of alternating current available at both ends of said section, another single wave rectifier at each end of said section, a coding contact at each end of said section, a transformer at each end of said section having its primary winding energized from said source and having its secondary windings so connected in series with the associated coding contact and the associated

another rectifier so that current impulses are alternately applied to opposite ends of said section of which each current impulse is poled so that it cannot flow through the track relay and its associated rectifier at that end but can flow through the track relay and its associated rectifier at the other end, relay means for checking the rectifying effectiveness of each rectifier connected in series with a secondary winding of such transformer, and electro-responsive decoding means controlled by said track relay and relay means.

4. In combination with a section of track divided from adjacent sections by insulating joints, a single wave rectifier for each end of said section, a track relay at each end of said section connected across the track rails and in series with the associated single wave rectifier at that end of said section, said rectifiers being so poled in their respective circuits that one rectifier allows current to flow from one rail and the other rectifier allows current to flow from the other rail of said section, a source of alternating current available at both ends of said section, another single wave rectifier at each end of said section, a coding contact at each end of said section, a transformer at each end of said section having its primary winding energized from said source and having its secondary winding so connected in series with the associated coding contact and the associated another rectifier so that current impulses are alternately applied to opposite ends of said section each current impulse being poled so that it cannot flow through the track relay and its associated rectifier at that end but can flow through the track relay and its associated rectifier at the other end, a check relay for checking the rectifying effectiveness of each rectifier connected in series with a track relay, a check relay for checking the rectifying effectiveness of each rectifier connected in series with the secondary winding of such transformer, a signal at each end of said section for governing the entrance of traffic into the section at that end, and a clearing circuit for each of said signals including front contacts of the track relay and front contacts of the check relays associated with that signal.

5. In combination with a section of track divided from adjacent sections by insulating joints, a transformer having a primary winding and a correspondingly poled secondary winding for each end of said section, a source of alternating current for energizing the primary windings of said transformers with corresponding instantaneous polarities, a track relay for each end of said section, two single wave rectifiers for each end of said section, said track relays and the secondary windings of said transformers being correspondingly connected in multiple across the track rails and each having one of said half-wave rectifiers included in series therewith, said rectifiers being so poled in their respective circuits that the half-wave of current supplied to the track rails by the secondary winding and the rectifier included in series therewith cannot flow through the associated track relay and the rectifier included in series therewith but can flow through the track relay and the rectifier included in series therewith at the opposite end, whereby impulses of current can flow alternately to the track relays at opposite ends of said section from such transformers, means for checking the rectifying effectiveness of said rectifiers, and signaling means controlled by said track relays.

6. In combination with a section of track di-

vided from adjacent sections by insulating joints, a transformer having a primary winding and a secondary winding for each end of said section, a source of alternating current for energizing the primary windings of said transformers, a track relay for each end of said section, two single wave rectifiers for each end of said section, said track relays and the secondary windings of said transformers being so connected in multiple across the track rails and each having one of said half-wave rectifiers included in series therewith so poled that the half-wave of current supplied to the track rails by the secondary winding and the rectifier included in series therewith cannot flow through the associated track relay and the rectifier included in series therewith but so that impulses of current flow alternately to the track relays at opposite ends of said section from such transformers, a check relay for checking the rectifying effectiveness of each of the rectifiers connected in series with the secondary windings of said transformers, a check relay for checking the rectifying effectiveness of each of the rectifiers connected in series with said track relays, and a signal governing the entrance of traffic into each end of said sections each controlled by the track relay and the two check relays located at that end.

7. In combination with a section of track divided from adjacent sections by insulating joints, a transformer having a primary winding and a secondary winding for each end of said section, a source of alternating current for energizing the primary windings of said transformers, a track relay for each end of said section, two single wave rectifiers for each end of said section, said track relays and the secondary windings of said transformers being so connected in multiple across the track rails and each having one of said half-wave rectifiers included in series therewith so poled in their respective circuits that the half-waves of current supplied to the track rails by the secondary winding and the rectifier included in series therewith at each end of said section cannot flow through the associated track relay and the rectifier included in series therewith but can flow through the track relay at the opposite end, whereby impulses of current flow alternately to the track relays at opposite ends of said section from the non-associated transformers, a check relay for each end of said section connected in multiple with the rectifier connected in series with the track relay at that end of said section, a check relay for each end of said section connected to receive rectified pulsating current from the secondary winding of the transformer at that end and constructed to pick up on pulsating current and drop away if this pulsating current is changed to alternating current due to failure of the rectifier supplying such pulsating current, and a signal at each end of said section governing the entrance of traffic into said section at that end and having a clearing circuit closed only if both of the check relays at that end assume their energized position and the associated track relay manifests clear traffic conditions.

8. In combination with a section of track divided from adjacent sections by insulating joints, a transformer having a primary winding and a correspondingly poled secondary winding for each end of said section, a source of alternating current for energizing the primary windings of said transformers with corresponding instantaneous polarities, a track relay for each end of said section, three single wave rectifiers for each end of

said section, said track relays and the secondary windings of said transformers being correspondingly connected in multiple across the track rails and each having one of said half-wave rectifiers included in series therewith, said rectifiers being so poled in their respective circuits that the half-waves of current supplied to the track rails by the secondary windings and the rectifiers included in series therewith cannot flow through the associated track relays and the rectifiers included in series therewith but so that they can flow through the non-associated track relays, whereby impulses of current flow alternately to the track relays at opposite ends of said section from the non-associated transformers, the third rectifier at each end of said section being connected in multiple with the track relay at that end and poled to allow the flow of pulsating current from the adjacent transformer around said track relay, means for checking the rectifying effectiveness of some of said rectifiers, and signaling means controlled by said track relays.

9. In combination with a section of track divided from adjacent sections by insulating joints, a transformer having a primary winding and a correspondingly poled secondary winding for each end of said section, a track relay for each end of said section, three single wave rectifiers for each end of said section, a source of alternating current connected to energize the primary windings of said transformers with corresponding instantaneous polarities, said track relays and the secondary windings of said transformers being correspondingly connected in multiple across the track rails at each end of said section and each having one of said half-wave rectifiers included in series therewith, said rectifiers being so poled that the half-wave of current supplied to the track rails by the secondary winding and the rectifier included in series therewith at one end of said section cannot flow through the associated track relay and the rectifier included in series therewith but so that it can flow through the track relay and rectifier included in series therewith at the other end, whereby impulses of current flow alternately to the track relays at opposite ends of said section from such transformers, the third rectifier at each end being connected in multiple with the track relay at that end and being poled to allow the flow of pulsating current from the adjacent transformer around said track relay, a check relay for checking the rectifying effectiveness of each of the rectifiers connected in series with said track relays, and a signal governing the entrance of traffic into each end of said section each controlled by the track relay and the two check relays located at that end.

10. In combination with a section of track divided from adjacent sections by insulating joints, a transformer having a primary winding and a correspondingly poled secondary winding for each end of said section, a track relay for each end of said section, three single wave rectifiers for each end of said section, a source of alternating current for energizing the primary windings of said transformers with corresponding instantaneous polarities, said track relays and the secondary winding of said transformers being correspondingly connected in multiple across the track rails at each end of said section and each having one of said half-wave rectifiers included

in series therewith so poled that the half-wave of current supplied to the track rails by the secondary winding and the rectifier included in series therewith cannot flow through the associated track relay and the rectifier included in series therewith but can flow through the track relay and associated rectifier at the other end, whereby impulses of current flow alternately to the track relays at opposite ends of said section from such transformers, the third rectifier at each end being connected in multiple with the track relay at that end and being poled to allow the flow of pulsating current from the adjacent transformer around said track relay, a check relay for each end of said section connected in multiple with the rectifier connected in series with the track relay at that end of said section, a check relay for each end of said section connected to receive rectifier pulsating current from the secondary winding of the transformer at that end and constructed to pick up on pulsating current but drop away if this pulsating current is changed to alternating current due to failure of the rectifier supplying such pulsating current, and a signal at each end of said section governing the entrance of traffic into said section at that end having a clearing circuit closed only if both of the check relays at that end assume their energized position and the associated track relay manifests proceed traffic conditions.

11. In combination with a section of track divided from adjacent sections by insulating joints, a single wave rectifier for each end of said section, a track relay at each end of said section connected in series with the associated single wave rectifier and connected across the rails of that end of said section, said rectifiers being so poled that one rectifier allows current to flow from one rail and the other rectifier allows current to flow from the other rail, a source of alternating current available at both ends of said section, another single wave rectifier at each end of said section, a transformer at each end of said section having its primary winding energized from said source and the secondary windings of which are connected in a particular polarity relation in series with said another rectifier, said other rectifiers being so poled that current impulses are alternately applied to opposite ends of said section each current impulse being of a polarity so that it cannot flow through the track relay and its associated rectifier at that end but can flow through the track relay and its associated rectifier at the other end, a check relay connected in multiple with each rectifier associated directly with a track relay, and electro-responsive means for each end of said section controlled by said track relay and check relay for that end.

12. In combination with a section of track divided from adjacent sections by insulating joints, a transformer having a primary winding and a secondary winding for each end of said section, a source of alternating current for energizing the primary windings of said transformers, a track relay for each end of said section, two half-wave rectifiers for each end of said section, said track relays and the secondary windings of said transformers being so connected in multiple across the track rails and each having one of said half-wave rectifiers included in series therewith so poled that the half-wave of current supplied to the track rails by the secondary winding and the rectifier included in series therewith

cannot flow through the associated track relay and the rectifier included in series therewith but so that impulses of current flow alternately to the track relays at opposite ends of said section from such transformers, a check relay for checking the rectifying effectiveness of each of the rectifiers connected in series with said track relays, and a signal governing the entrance of traffic into each end of said sections each controlled by the track relay and the check relay located at that end.

13. In combination with a section of track divided from adjacent sections by insulating joints, a transformer having a primary winding and a secondary winding for each end of said section, a source of alternating current for energizing the primary windings of said transformers, a track relay for each end of said section, two half-wave rectifiers for each end of said section, said track relays and the secondary windings of said transformers being connected in multiple across the track rails and each having one of said half-wave rectifiers included in series therewith so poled that the half-wave of current supplied to the track rails by the secondary winding and the rectifier included in series therewith cannot flow through the associated track relay and the rectifier included in series therewith but so that impulses of current flow alternately to the track relays at opposite ends of said section from such transformers, a check relay for checking the rectifying effectiveness of each of the rectifiers connected in series with the secondary windings of said transformers, a signal at each end of said section for governing the movement of traffic into that end of said section, and means for controlling each of said signals by the track relay and the check relay associated therewith.

14. In combination with a section of track divided from adjacent sections by insulating joints, a transformer having a primary winding and a correspondingly poled secondary winding for each end of said section, a source of alternating current for energizing the primary windings of said transformers to corresponding relative polarities, a track relay for each end of said section, two single wave rectifiers for each end of said section, said track relays and the secondary windings of said transformers being correspondingly connected in multiple across the track rails and each having one of said half-wave rectifiers included in series therewith, said rectifiers being so poled in their respective circuits that the half-waves of current supplied to the track rails by the secondary winding and the rectifier included in series therewith at each end of said section cannot flow through the associated track relay and the rectifier included in series therewith but can flow through the track relay at the opposite end, whereby impulses of current flow alternately to the track relays at opposite ends of said section from the non-associated transformers, a check relay for each end of said section connected to receive rectified pulsating current from the secondary winding of the transformer at that end and constructed to pick up on pulsating current and drop away if this pulsating current is changed to alternating current due to failure of the rectifier supplying such pulsating current, and a signal at each end of said section governing the entrance of traffic into said section at that end and having a clearing circuit closed only if the check relay at that end assumes its energized position and the asso-

ciated track relay manifests clear traffic conditions.

15. In a combination with a section of track divided from adjacent sections by insulating joints, a source of alternating current, a transformer having a primary and a secondary winding for each end of said section and having its primary winding energized from said source, a polar track relay for each end of said section, a half-wave rectifier for each end of said section, circuit means for connecting the secondary windings of said transformers and said polar track relays in multiple across the track rails at each end of said section with the associated rectifier connected in series with the secondary winding of the transformer and so poled in the circuit means that pulses of pulsating current may flow from each secondary winding through the winding of the polar track relay at the opposite end of the section in a direction to actuate the same but not through the winding of the polar relay at the same end of the section in a direction to actuate the same, means for checking the rectifying effectiveness of said rectifiers, and a signal at each end of said section for governing the movement of traffic into said section controlled by the polar track relay at that end.

16. In combination with a section of track divided from adjacent sections by insulating joints, a source of alternating current, a transformer having a primary and a secondary winding for each end of said section and having its primary winding energized from said source, a polar track relay for each end of said section, a half-wave rectifier for each end of said section, circuit means for connecting the secondary windings of said transformers and said polar track relays in multiple across the track rails at each end of said section with the associated rectifier connected in series with the secondary winding of the transformer and so poled in the circuit means that pulses of pulsating current from each secondary winding may actuate the polar track relay at the opposite end of said section but can not actuate the polar track relay at the same end, a check relay at each end of said section connected to be energized from the secondary winding of the transformer at that end of said section and to assume its energized position only if such rectifier functions to deliver pulsating current, and a signal at each end of said section for governing the movement of traffic into said section at its end controlled by the polar track relay and the check relay at that end of said section.

17. In combination with a section of track divided from adjacent sections by insulating joints, a source of alternating current, a transformer having a primary and a secondary winding for each end of said section and having its primary winding energized from said source, a polar track relay for each end of said section, a half-wave rectifier for each end of said section, circuit means for connecting the secondary windings of said transformers and said polar track relays in multiple across the track rails at each end of said section with the associated rectifier connected in series with the secondary winding of the transformer and so poled in the circuit means that pulses of pulsating current may actuate the polar track relay at the opposite end but not the polar track relay at the same end, a check relay at each end of said section connected to be energized from the secondary winding of the transformer at that end of said section and to

assume its energized position only if such rectifier functions to deliver pulsating current, and a signal at each end of said section for governing the movement of traffic into said section at its end, and a circuit for each signal including a front contact of the associated check relay and controlled by a contact of the associated polar track relay.

18. In combination with a section of track divided from adjacent track by insulating joints, a transformer for each end of said section each having a secondary winding, a rectifier included in series in each of said secondary windings, a source of alternating current for energizing the primary windings of said transformers, the primary windings of said transformers being energized by currents of such polarities and the secondary winding and the rectifiers being so poled that impulses of potential of alternate opposite polarities are applied alternately at opposite ends to the track rails of said section, a polarity responsive relay connected across the rails at each of the ends of said section so connected that each relay responds only to the impulses applied to the opposite end of said section, means for
